DESIGN.

B. E. STONE,

MUSIC CABINET.

APPLICATION FILED JUNE 18, 1918.

52,499.

Patented Sept. 24, 1918.

Bert E. Stone Inventor
Victor J. Evans Attorney

UNITED STATES PATENT OFFICE.

BERT E. STONE, OF PLATTSBURG, NEW YORK.

DESIGN FOR A MUSIC-CABINET.

52,499.

Specification for Design.

Patented Sept. 24, 1918.

Application filed June 18, 1918. Serial No. 240,682. Term of patent 14 years.

To all whom it may concern:

Be it known that I, BERT E. STONE, a citizen of the United States, residing at Plattsburg, in the county of Clinton and State of New York, have invented a new, original, and ornamental Design for Music-Cabinets, of which the following is a specification, reference being had to the accompanying drawing, forming a part thereof.

The figure is a perspective view of a music cabinet, showing my new design.

I claim:

The ornamental design for a music cabinet, as shown.

BERT E. STONE.

Witnesses:

CHARLES J. NUT,
MAUDE MACOMBER.
